DESIGN FOR A DAMPER OPERATOR

Homer E. Malone, Milwaukee, Wis., assignor to Perfex Corporation, Milwaukee, Wis., a corporation of Wisconsin

Application January 27, 1941, Serial No. 98,401

Term of patent 7 years

To all whom it may concern:

Be it known that I, Homer E. Malone, a citizen of the United States and a resident of Milwaukee, in the county of Milwaukee and State of Wisconsin, have invented a new, original, and ornamental Design for a Damper Operator, of which the following is a specification, reference being had to the accompanying drawing, forming a part thereof.

I claim:

The ornamental design for a damper operator, substantially as shown.

HOMER E. MALONE.
